WIRE GAUGE

Alfred G. Natzke, New York, N. Y., assignor to
 Lamar Slide Fastener Corp., New York, N. Y.,
 a corporation of New York

Application August 7, 1946, Serial No. 689,065

10 Claims. (Cl. 33—174)

1

This invention relates to a device to be employed in connection with a step in the manufacture of slide fasteners.

In the following description, reference will be made to one particular method for the manufacture of scoops or slide fastener elements for slide fasteners, but it is to be clearly understood that this is done solely for the sake of perspicuity, and that my invention and any apparatus embodying my invention can be applied to the manufacture of fastener elements by other methods. Likewise, a person skilled in the art, exercising mechanical ingenuity, could modify the details of my invention and adapt it to applications somewhat different from the one herein disclosed.

I preferably contemplate to apply my invention to a method for the manufacture of fastener elements which comprises forming on a wire or strip stock a series of embryo fastener elements, by passing the original wire or strip through a machine which will be designated, following a practice common in the art, as the "wire rolling mill." Likewise, the word "wire" will be used to designate any and all stock materials used in the manufacture of fastener elements, it being understood that this is done for the sake of brevity and implies no limitation, and especially does not imply that the cross section of the stock material must be circular.

As is well known in the art, a fastener element comprises a head and a pair of spaced jaws, which jaws are to be closed by clamping them on the edge of a tape to form a fastener stringer. The head comprises a projection and a mating recess on the opposite side.

As the wire is passed through the rolling mill, it is deformed to acquire the shape illustrated in Figs. 2 and 3, that is, it is flattened and a series of head projections and mating recesses are coined therein, which recesses and projections constitute the embryo elements. Said embryo elements closely follow each other, so that there is no waste involved in cutting the rolled wire into individual fastener elements.

It is well known that the finished fastener elements must conform to certain requirements of uniformity in their shapes and dimensions, in order to assure a smooth and even operation of the finished fastener. Relatively slight defects in the conformation of the fastener elements sharply lower the quality of the finished fastener, and in extreme cases may render this latter inoperative.

Therefore, in order that satisfactory fastener

elements may be produced by a shearing operation from a rolled wire which has defined thereon the embryo elements, said rolled wire also must conform to certain requirements. My invention is directed to a control device to be applied to the wire rolling mill, which device constantly gages the rolled wire, to see that it is properly formed, and if it is not properly formed, that is, if the irregularities appearing therein after the rolling operation exceed certain predetermined narrow tolerances, automatically stops the wire rolling mill and also signals to the operator which of the properties of the rolled wire is unsatisfactory, to permit prompt correction of the defect without any further investigation.

The device to which this invention relates is concerned with three properties of the rolled wire. The first is the overall width of the wire, identified as *a* in Fig. 2. The second is the overall height of the head projections, identified as *b* in Fig. 2. The third is the relative centering of the head projections and recesses. These latter, if the rolling operation is properly carried out, will be in exactly superimposed relationship, so that the heads of the finished fastener elements may engage each other smoothly and precisely, as required. However, if the rolling mill does not function well, projections and recesses will be laterally shifted with respect to each other, and the finished elements will be defective. In such a case, production must be stopped, and the defect repaired, so that head projections and recesses may occupy the same centered position on the rolled wire, and be truly "mating."

Inasmuch as the device to which this invention relates gages the three properties aforementioned, and also stops the wire rolling mill or like machine if the same are not satisfactory, the device will be designated as a "combined gage control mechanism," but the single word "gage" will be often used alone for the sake of brevity.

It is the general object of this invention to provide a combined gage control mechanism for a wire rolling mill used in the manufacture of slide fastener elements, which gage constantly checks the overall width of the rolled wire, the height of the heads, and the registering of the head projections and head recesses, and automatically stops the rolling mill if any one of these three factors does not conform to predetermined requirements.

Another object is to provide such a combined gage control mechanism which, while stopping the rolling mill as hereinbefore indicated, will also signal to the operator and identify which

of the three factors hereinbefore set forth is defective, thus enabling the operator to know at once where the trouble lies.

A further object is to provide a gage control mechanism of the character indicated which is endowed with a high sensitivity, and which is absolutely foolproof in its operation.

A still further object is to provide a gage control mechanism of the character indicated which attains the desired results with a maximum simplicity of structure, and consequent economy of manufacture.

Other related and ancillary objects of this invention will clearly appear as the description proceeds.

In the drawings:

Fig. 1 is a longitudinal elevational view of a combined gage control mechanism according to the invention.

Fig. 2 is a perspective view of a fragment of the rolled wire at a greatly enlarged scale.

Fig. 3 is a perspective view of the element shown in Fig. 2, but viewed from the bottom.

Fig. 4 is a top plan view of the mechanism of Fig. 1.

Fig. 5 is a cross-section of the mechanism of Fig. 1, taken on the line 5—5 of Fig. 4, looking in the direction of the arrows.

Fig. 6 is a bottom plan view of the mechanism of Fig. 1.

Fig. 7 is an elevational view at an enlarged scale of a detail of Fig. 1.

Referring now in detail to the drawings, 10 indicates a support or base for the gage control mechanism, which can be mounted on or in any suitable way attached to the wire rolling mill or like machine to which this invention is to be applied. The wire, indicated at 11, enters the gage between two superimposed rollers 12 and 13 with the head projections 14 thereof on the top. The top roller 12 is provided with indentations 16 to receive the projections 14, whereas the bottom roller 13 is provided with protuberances 17 to engage the mating recesses 15. The engagement of the protuberances and indentations of the rollers with the recesses and projections respectively of the rolled wire maintains the rollers in alined relationship with these latter.

Rigidly attached to the base 10 there is a stud or pin 18 upon which is pivotally mounted a forked support 19 embodying two arms 20. The arms 20 are rigid with a shaft or pin 21 on which the top roller 12 is rotatably mounted. Alternatively, the roller 12 could be keyed to the shaft 21 and this latter be rotatably supported in the arms 20. A lever 22 is inserted into a seat 23 in one of the arms 20. A tension spring 24 is attached to the end of lever 22 and also to the base 10, and constantly urges the whole forked support 19 with its attachments downwardly. Thus the top roller 12 is resiliently urged towards the bottom roller 13 firmly to engage the wire 11 passing therebetween. A support 25 is attached to the bottom of the base 10 and has a shaft or pin 26 secured in invariable positioned relationship thereto. The pin 26 has the bottom roller 13 freely mounted thereon, but said bottom roller, in addition to being rotatable on the shaft 26, is also slidably axially thereon by a limited amount. Alternatively, as in the case of the top roller, the bottom roller 13 could be keyed to the shaft 26, and this latter rotatably supported in the support 25, or any other equivalent arrangement could be employed. At any rate, the two rollers firmly grip the wire and rotate as it advances into the

gage. The lateral position of the wire is determined by the engagement of its head projections with corresponding indentations of the top roller. As long as the embryo elements are properly formed, that is the head projections and recesses are relatively centered, the bottom roller remains in exact underlying relationship to the top roller, inasmuch as it has protuberances which engage the head recesses of the wire. But if the head projections are laterally displaced with respect to the head recesses, due to faulty operation of the wire rolling mill, the bottom roller is forced to follow the head recesses and becomes axially displaced with respect to the top roller. It is to be understood that the roles of the two rollers could be reversed, and that the details of the assembly could be modified within the scope of the invention, as long as means are provided equivalent to those described for producing a lateral displacement of one roller with respect to the other in response to any defective conformation of the embryo fastener elements.

Two levers 27, pivoted at 28 to the bottom of the base 10 have points 29 engaging the bottom roller 13 at each side thereof. The levers 27 are connected to one another at the end opposite the points 29, by a bridge 30 pivotally connected at 31 to each lever 27. Between the two levers 27 there is a bridge 32 fixed to the base 10, and electrically connected to a wire schematically indicated at 33. Each lever 27 carries a contact 34 connected to a wire schematically indicated at 35. The wires 33 and 35 form part of a circuit including a signal light or other signal, which circuit is closed whenever either one of the contacts 34 touches the bridge 32. As long as the bottom roller 13 is exactly underlying the top roller 12, neither contact 34 touches the bridge 32, but as soon as the roller 13 ceases to be centered and shifts slightly, to one or the other side, one of the points 29 is urged away from its normal position, causes the corresponding lever 27 to swing about its pivot 28, making contact and lighting the light.

The bridge 30 has a V-shaped recess 36 in the center thereof, against which bears a roller 37 connected to a spring 38 of a micro-switch 39. When the levers 27 are in their normal position, that is in the position they assume when the roller 13 underlies the roller 12, said roller 37 engages said recess 36 at its central or deepest portion, and the micro-switch 39 does not make contact. However, if either lever 27 is caused to swing as explained above, the roller 37 will ride up one of the two inclined planes which make up the recess 36 of the bridge 30 and will move to the left, as viewed in Fig. 6, thus making contact in the micro-switch 39 and shutting off the motor which operates the rolling mill.

As soon as the rolled wire has passed between the rollers 12 and 13 and under the forked support 19, it passes under a rounded point 40 carried on or forming part of a lever 41 pivoted at 42 to a support block 43 suitably attached to the base 10. Lever 41 is guided in the vicinity of its free end by a bridge 44 attached to a support block 45. The free end of the lever 41 that is, the end opposite to the pivoted end, defines an inclined plane 46, which is slanted upwards and outwards, that is to say, to the left from bottom to top, as viewed in Fig. 1. A roller 47 bears against the inclined plane 46 and is carried by an arm 48 attached to a spring 49 of a micro-switch 50. The arm 48 bears against an inclined plane

51 of a lever 52 pivoted at 53 to the support 54 of the micro-switch 50. The arm 48 is provided at its left bottom edge with a hook projection 55. The lever 52 has a corresponding hook projection 56, best shown in Fig. 7.

The rounded point 40 of the lever 41 rides over the head projections 14 of the rolled wire 11. The weight of the lever itself keeps the point 40 in engagement with the head projections; it is to be understood however that independent means could be provided, were the device so constructed as to make this desirable, to assure said engagement, and said means could comprise a spring or springs. If the height of one of said head projections is less than the predetermined desired height, the point 40 drops, and its motion is transmitted with considerable amplification to the free end of the lever 41. As a result, the inclined plane 46 urges the roller 47 to the left, as viewed in Fig. 1, to make contact in the micro-switch 50 shutting off the motor which operates the rolling mill. In general, however, if only one or very few heads are defective, the lever 41 would not remain in its depressed position and the arm 48 in its leftwardly position, wherein it closes the switch, for a long enough time properly to actuate the switch. For this reason a lock is provided to hold the arm 48 in said leftwardly position, once it has assumed it, and this lock consists of the hook projection 55 of the arm 48, the hook projection 56 of the lever 52, and the spring 57 which constantly urges the lever 52 upwards. Once the arm 48 has moved far enough to the left for the two hook projections to engage each other, it cannot return to the right unless it is unlocked by depressing the lever 52, against the action of the spring 57, until the hooks 55 and 56 are disengaged from each other. When in its locked position, illustrated in Fig. 7, the lever 52 touches a contact 58 attached to a bridge 59. The bridge 59 is electrically connected to a wire schematically indicated at 60, while the lever 52 is electrically connected to a wire schematically indicated at 61. Both wires 60 and 61 are part of an electric circuit which includes a signal light, or other signal, different from the signal connected to the wires 33 and 35.

Normally the arm 48, by bearing against the inclined plane 51, maintains the lever 52 in a position sufficiently depressed to prevent this latter from touching the contact 58. But when the dropping of the lever 41, due to insufficient height of a head projection, causes engagement of the two hook projections 55 and 56, as hereinbefore set forth, the lever 52 is allowed to rise enough to touch the contact 58, and the signal is energized.

After contacting the point 40, the rolled wire passes under a bridge 62. Said bridge 62 is adjustably mounted on the base 10 by means of pivot screws 63 attached to bracket 64 and adjusting screw 65. The pivot screws 63 define aligned centers about which the bridge 62 is pivotable to raise it or lower it by turning the adjusting screw 65. Said bridge 62 is provided internally with a shoulder 66 which forms a guide for one edge of the rolled wire, and is suitably positioned relatively to the top roller so that the wire is caused to follow a substantially straight line. Slidably mounted internally of the bridge 62 there is a block 67 which can slide by a small distance at 90° to the wire. The end of the block 67 opposite to that which engages the edge of the wire is in contact with a plate 68 and this latter with a rounded point 69 of a lever 70 pivoted at

71 to the frame 10. Said lever 70 has mounted thereon a fork 72 the two fingers of which straddle a pin 73 attached to a bridge 74.

The fork 72 is electrically connected to a wire schematically indicated at 75, while the bridge 74 and the pin 73 are electrically connected to a wire schematically indicated at 76. Wires 75 and 76 form part of an electric circuit which includes a signal light or other signal, different both from the signal connected to wires 33 and 35 and from the signal connected to wires 60 and 61. A tension spring 77 operatively connects the lever 70 to the base 10, and constantly urges the point 69 of the lever 70 against the plate 68, said plate against the block 67, and this last against the edge of the wire 11 that is not in contact with the shoulder 66. The normal position of the lever 70, that is the position it assumes under the urging of the spring 77, when the width of the rolled wire is within predetermined tolerance limits, is such that there is a slight clearance between the pin 73 and the two fingers of the fork 72, so that the circuit including the signal light remains open.

The end of the lever 70 opposite the rounded point 69 has a V-shaped recess 78 defined by two inclined planes. A roller 79 mounted on a spring 80 of a micro-switch 81 engages the recess 78. In the normal position of the lever 70, said roller 79 is situated in the central or deepest portion of the recess 78, and the micro-switch does not make contact. However, if the width of the rolled wire does not conform to specifications, that is, if it exceeds the aforementioned tolerance limits by being too large or too small, the block 67 will be forced away or allowed to move towards the shoulder 66 under the urging of the spring 77, as the case may be. The point 69 of the lever 70 will follow the motion of the block, and consequently the lever 70 will swing away from its normal position in one or the other direction. Then the roller 79 will ride up one of the two inclined planes which define the recess 78, will be forced to the left, as viewed in Fig. 6, and will cause the micro-switch 81 to make contact, shutting off the motor which operates the wire rolling mill. Concurrently one of the two fingers of the fork 72 will contact the pin 73, closing the circuit of the wires 75 and 76, and energizing the signal. It is obvious that arrangements other than the one described could be used to swing the lever 70 in response to any departure of the width of wire from the predetermined permissible limits.

It is seen therefore, that the present invention provides in one unit a gage control device for the three properties of the wire discussed at the beginning of this specification, namely, the width of the wire, the height of the heads, and the registering of the recesses and projections which form the heads. A defect in any one of these three properties will result in automatically stopping the wire rolling mill, and also in signalling to the operator which of the three properties is defective, since a different signal is provided for each one of them.

While I have taken into account defects in the width of the wire or in the registration of the head projections and recesses in either of the two possible directions, that is, while I contemplate that the wire may be either too wide or too narrow and that the head projections may be shifted either to the right or to the left of their centered position with respect to the head recesses, I consider that the only defect in the height of

the heads to be taken into account is an insufficient height, such as may be due to the filling of a pocket in the roller of the wire rolling mill. However, if it were so desired, a person skilled in the art, knowing the principles of this invention and bearing the teachings of this specification in mind, could so modify the device as to render it sensitive also to any excess in the height of the heads, and such a modification could be accomplished by the exercise of no more than mechanical skill.

In the preferred embodiment described, the part of the gage which responds to defects in the height of the heads has been provided with a lock arrangement to allow it to operate effectively no matter how short the defective portion of the wire may be. The remaining parts of the gage have not been provided with any such lock arrangement, for the reason that in practice I find that if there are defects in the width of the wire or in the registration of the head projections and recesses, such defects extend for a sufficiently long portion of the wire to allow the gage to operate without the provision of a lock arrangement. However, if it were so desired, lock arrangements could be introduced in the parts of the gage which respond to defects in the width of the wire or in the registration of the head projections and recesses, and such lock arrangements might be similar in structure to the lock arrangement described or might consist of equivalent mechanical devices, such as may be contrived by a person skilled in the art being in possession of teachings of this specification.

It is to be understood that, for any of the properties of the wire to which this invention is related, there are certain predetermined tolerances within which the wire is acceptable. The gage will be designed correspondingly to said predetermined tolerances, and variations in said tolerances will result in variations in the particular proportions and dimensions of the various parts of the device, such as the various levers and associated means. These variations are a matter of judicious design and can be provided by a person skilled in the art. It is not thought necessary therefore to discuss them at length here. It is noted, however, that a device according to this invention can be rendered as sensitive as may be desirable in practice under any possible conditions, by properly dimensioning and arranging the various component parts thereof.

It is understood that whenever the wire rolling mill stops as a result of the operation of this gage, the defective part of the rolled wire can be eliminated so that no defective fastener elements will be finally produced, and, knowing what the defect is, proper steps can be taken to correct the same. As to such steps, they are not material in discussing this invention and need not be gone into here.

While I have described one preferred embodiment of my invention for the sake of illustration, it is understood that many modifications and adaptations may be made therein by persons skilled in the art, without departing from the spirit of the invention or exceeding the scope of the appended claims.

I claim:

1. In a mechanism of the character described for gauging the alignment of the head projections and the head recesses of connected embryo scoops, which projections and recesses are produced on opposite sides of a continuous length of wire by deformation thereof, means for longitudinally moving said deformed wire, a first roller means engaging the head projections of said embryo slide fastener elements, a second roller means engaging the head recesses of said embryo slide fastener elements, said respective roller means normally being in lateral alignment and one of said roller means being axially movable with respect to the other, said first and second roller means maintaining a normal positioned relationship as long as said head projections and the corresponding head recesses are centered with respect to one another and becoming relatively displaced by an embryo slide fastener element when said head projections and the corresponding head recesses thereof are not so centered, and lever means operatively associated with at least one of said roller means, said lever means being displaceable from a normal position in response to a relative displacement of said roller means.

2. In a mechanism of the character described for gauging the alignment of the head projections and the head recesses of connected embryo scoops, which projections and recesses are produced on opposite sides of a continuous length of wire by deformation thereof, means for longitudinally moving said deformed wire, a first roller means engaging the head projections of said embryo slide fastener elements, a second roller means engaging the head recesses of said embryo slide fastener elements, said respective roller means normally being in lateral alignment and one of said roller means being axially movable with respect to the other, said first and second roller means maintaining a normal positioned relationship as long as said head projections and the corresponding head recesses are centered with respect to one another and becoming relatively displaced by an embryo slide fastener element when said head projections and the corresponding head recesses thereof are not so centered, and lever means operatively associated with at least one of said roller means, said lever means being displaceable from a normal position in response to a relative displacement of said roller means.

25 3. In a mechanism of the character described for gauging the alignment of the head projections and the head recesses of connected embryo scoops, which projections and recesses are produced on opposite sides of a continuous length of wire by deformation thereof, means for longitudinally moving said deformed wire, a first roller means engaging the head projections of said embryo slide fastener elements, a second roller means engaging the head recesses of said embryo slide fastener elements, said respective roller means normally being in lateral alignment and one of said roller means being axially movable with respect to the other, resilient means for urging said first and second roller means towards one another firmly to grip the wire therebetween, said first and second roller means maintaining a normal positioned relationship as long as said head projections and the corresponding head recesses are centered with respect to one another and becoming relatively displaced by an embryo slide fastener element when said head projections and the corresponding head recesses thereof are not so centered, and lever means operatively associated with at least one of said roller means, said lever means being displaceable from a normal position in response to a relative displacement of said roller means.

30 4. In a mechanism of the character described for gauging the alignment of the head projections and the head recesses of connected embryo scoops, which projections and recesses are produced on opposite sides of a continuous length of wire by deformation thereof, means for longitudinally moving said deformed wire, at least one roller having projections along the periphery thereof engaging the head recesses of said embryo slide fastener elements, at least one second roller having recesses along the periphery thereof engaging the head projections of said embryo slide fastener elements, said first and second roller maintaining a normal positioned relationship as long as said head projections and the corresponding head recesses are centered with respect to one another and being axially displaceable with respect to one another by an embryo slide fastener element when said head projections and the corresponding head recesses thereof are not so centered, and lever means operatively associated with at least one of said rollers, said lever means being displaceable from a normal position in response to a relative displacement of said rollers.

45 5. In a mechanism of the character described for gauging the alignment of the head projections and the head recesses of connected embryo

scoops, which projections and recesses are produced on opposite sides of a continuous length of wire by deformation thereof, means for longitudinally moving said deformed wire, a base, a first roller rotatably attached to said base and having projections along the periphery thereof engaging the head recesses of said embryo slide fastener elements, a second roller rotatably attached to said base and having recesses along the periphery thereof engaging the head projections of said embryo slide fastener elements, one of said rollers being axially slidably with respect to said base, said first and second rollers maintaining a normal aligned position relationship as long as said head projections and corresponding head recesses of an embryo slide fastener element are centered with respect to one another, and said axially slidably roller being displaced away from a normal position by an embryo slide fastener element when said head projections of said embryo slide fastener elements and the corresponding head recesses thereof are not relatively centered, means for urging at least one of said rollers towards the other firmly to grip the wire therebetween, and lever means associated with said axially slidably roller, said lever means being swingable from a normal position in response to sliding of said axially slidably roller.

5. In a mechanism of the character described for gauging the alignment of the head projections and the head recesses of connected embryo scoops, which projections and recesses are produced on opposite sides of a continuous length of wire by deformation thereof, means for longitudinally moving said deformed wire, a base, a first roller rotatably attached to said base and having projections along the periphery thereof engaging the head recesses of said embryo slide fastener elements, a second roller rotatably attached to said base and having recesses along the periphery thereof engaging the head projections of said embryo slide fastener elements, one of said rollers being axially slidably with respect to said base, said first and second rollers maintaining a normal aligned position relationship as long as said head projections and corresponding head recesses of an embryo slide fastener element are centered with respect to one another, and said axially slidably roller being displaced away from a normal position by an embryo slide fastener element when the head projections and the corresponding head recesses thereof are not relatively centered, resilient means for urging at least one of said rollers towards the other firmly to grip the wire therebetween, and lever means pivoted in said base and having portions laterally engaging said axially slidably roller, whereby said lever means are swingable in response to axial motion of said axially slidably roller.

6. In a mechanism of the character described for gauging the alignment of the head projections and the head recesses of connected embryo scoops, which projections and recesses are produced on opposite sides of a continuous length of wire by deformation thereof, means for longitudinally moving said deformed wire, first roller means engaging the head projections of said embryo slide fastener elements, second roller means engaging the head recesses of said embryo slide fastener elements, said first and second roller means maintaining a normal positioned relationship as long as said head projections and the corresponding head recesses are centered with respect to one another and becoming relatively displaced by an embryo slide fastener element when said head projections and the corresponding head

recesses thereof are not so centered, lever means operatively associated with at least one of said roller means, said lever means being displaceable from a normal position in response to relative displacement of said roller means, a cam surface operatively connected to said lever means, a follower operatively associated with said switch means and engaging said cam surface, said lever means when they become displaced by a predetermined amount from their normal position actuating said cam surface to displace said follower.

7. In a mechanism of the character described for gauging the alignment of the head projections and the head recesses of connected embryo scoops, which projections and recesses are produced on opposite sides of a continuous length of wire by deformation thereof, means for longitudinally moving said deformed wire, a first roller means engaging the head projections of said embryo slide fastener elements, a second roller means engaging the head recesses of said embryo slide fastener elements, said respective roller means normally being in lateral alignment and one of said roller means being axially movable with respect to the other, said first and second roller means maintaining a normal positioned relationship as long as said head projections and the corresponding head recesses are centered with respect to one another and becoming relatively displaced by an embryo slide fastener element when said head projections and the corresponding head recesses thereof are not so centered, and lever means operatively associated with at least one of said roller means, said lever means being displaceable from a normal position in response to a relative displacement of said roller means, and means operatively connected with and actuated upon the displacement of said lever from normal position for signalling such movement.

40 8. In a mechanism of the character described for gauging the alignment of the head projections and the head recesses of connected embryo scoops, which projections and recesses are produced on opposite sides of a continuous length of wire by deformation thereof, means for longitudinally moving said deformed wire, at least one roller having projections along the periphery thereof engaging the head recesses of said embryo slide fastener elements, at least one second roller having recesses along the periphery thereof engaging the head projections of said embryo slide fastener elements, said first and second roller maintaining a normal positioned relationship as long as said head projections and the corresponding head recesses are centered with respect to one another and being axially displaceable with respect to one another by an embryo slide fastener element when said head projections and the corresponding head recesses thereof are not so centered, and lever means operatively associated with at least one of said rollers, said lever means being displaceable from a normal position in response to relative displacement of said rollers, and means operatively connected with and actuated upon the displacement of said lever from normal position for signalling such movement.

45 9. In a mechanism of the character described for gauging the alignment of the head projections and the head recesses of connected embryo scoops, which projections and recesses are produced on opposite sides of a continuous length of wire by deformation thereof, means for longitudinally moving said deformed wire, a base, a first roller rotatably attached to said base and having projections along the periphery thereof engaging the

11

head recesses of said embryo slide fastener elements, a second roller rotatably attached to said base and having recesses along the periphery thereof engaging the head projections of said embryo slide fastener elements, one of said rollers being axially slidable with respect to said base, said first and second rollers maintaining a normal aligned position relationship as long as said head projections and corresponding head recesses of an embryo slide fastener element are centered with respect to one another, and said axially slid- 10 able roller being displaced away from a normal position by an embryo slide fastener element when the head projections of said embryo slide fastener elements and the corresponding head recesses thereof are not relatively centered, means for urging at least one of said rollers towards the other firmly to grip the wire therebetween, and lever means associated with said axially slid- 15 able roller, said lever means being swingable from a normal position in response to sliding of said axially slid-able roller, and means operatively connected with and actuated upon the displacement of said lever from normal position for signalling such movement.

10. In a mechanism of the character described for gauging the alignment of the head projections and the head recesses of connected embryo scoops, which projections and recesses are produced on opposite sides of a continuous length of wire by 30 longitudinal deformation thereof, means for longitudinally moving said deformed wire, first roller means engaging the head projections of said embryo slide fastener elements, second roller means engaging the head recesses of said embryo slide fastener elements, said first and second roller means main-

12

taining a normal positioned relationship as long as said head projections and the corresponding head recesses are centered with respect to one another and becoming relatively displaced by an embryo slide fastener element when said head projections and the corresponding head recesses thereof are not so centered, lever means operatively associated with at least one of said roller means, said lever means being displaceable from a normal position in response to relative displacement of said roller means, a cam surface operatively connected to said lever means, a follower operatively associated with said switch means and engaging said cam surface, said lever means when they become displaced by a predetermined amount from their normal position actuating said cam surface to displace said follower, and means operatively associated with and actuated upon the displacement of said follower from normal position for signalling such movement.
